LOCK FOR BAGS

Attilio Benigni, Rome, Italy

Application June 28, 1938, Serial No. 216,321
In Italy June 28, 1937

2 Claims. (Cl. 70—312)

The present invention refers to locks for bags, and more particularly to a locking device for ladies' hand bags and the like.

One object of the invention is to provide a lock of this type which can be easily and instantaneously operated in an almost unnoticed manner.

Another object of the invention is to produce a combination lock for hand bags which is operated without a key.

Still other objects are to provide locks of the type described which have small dimensions and a pleasant appearance and which can be easily and cheaply manufactured.

One embodiment of the device according to the invention is illustratively exemplified in the accompanying drawing, in which:

Fig. 1 shows in perspective a frame for a lady's bag provided with the device according to invention.

Fig. 2 is an axial section through the combination lock connected with said device.

Fig. 3 is a section according to line III—III of Fig. 2.

With reference to the drawing and first to Fig. 1 a bag 1, shown in dot and dash lines is provided with a frame 2 having hinge joints 3 and cross bars 4—5. The cross bar 4 is tubular and encloses a sliding bar 6 provided with a plurality of recesses 7. Ball-shaped locking elements 9 are carried by pins 10 projecting from the cross bar 5, so as to be capable of entering the recesses 7 through holes 8 in the cross bar 4 and to be locked in said holes by a longitudinal displacement of the bar 6 towards the right (Fig. 1). A key 11 is fixed to the sliding bar 6 and cooperates with a slot 12 in the tubular bar 4 to prevent the bar 6 from rotating around its own axis thus holding the recesses 7 in register with the holes 8. A knob 13 is fixed to one end of the sliding bar 6 and serves to push the same towards the right (Fig. 1).

According to the present invention, this locking device is combined with a special combination lock generally indicated by 14 which serves to block the sliding bar 6 in its locking position and to prevent opening of the frame and bag unless the combination lock is first restored to a previously established position.

With reference to Figures 2 and 3, the lock 14 consists of a tubular fixed body 15 carrying a fixed ring 16. In the upper part of the ring 16, there is provided a cavity 17 to receive a tooth 18 when the bar 6 is pulled towards the left by means of the knob 13 (s. also Fig. 1). Said mo-

tion to the left of the bar 6 entrains the moveable body 19 of the lock connected to said bar by means of a threaded coupling 20.

The moveable body 19 comprises a cylinder having a radial slot in its midportion and on each side of said slot an axial bore. Two sliding points 21 and 22 disposed in said bores project into the central slot and are pressed one towards the other by springs 23 and 24. The spring 23 is controlled by a screw 25 and the spring 24 is held in position by a screw 26 which is provided with a knurled knob 27.

The two sliding points 21 and 22 are urged against the bevelled edges of a tooth plate 28 located in the central slot of the cylinder body 19 and provided with three teeth 18—29—30. The teeth 18, 29 and 30 have radial front faces and bevelled rear faces cooperating with flanges 31—32—33 of three rings 34—35—36 in locking position and when the bar 6 is moved from open to locking position, respectively. The passage of the teeth 18—29—30 from the position illustrated (locking position) to the opening position (in which the tooth 18 is lodged in the cavity 17 of the ring 16, the tooth 29 takes the position previously occupied by tooth 18 and the tooth 30 takes the position previously occupied by tooth 29) is effected through channels provided in the flanges 31—32—33. In Fig. 2 the channel 37 of the flange 31 is visible while in Fig. 3, there is shown the channel 38 of flange 33.

The plate 28 is axially displaced together with the moveable body 19 of the lock; it also can carry out a movement in its own plane in radial direction. When the bar 6 and the cylinder body 19 are moved from the open position (not illustrated) to the locking position (Fig. 2) the bevelled rear faces of the teeth 18, 29, 30, which do not register with the channels in the flanges 31—32—33, cooperate with said flanges to depress the plate 28 into a position in which the teeth 18, 29 and 30 can pass below the flanges 31, 32 and 33, whereupon the spring controlled points 21, 22 cooperate with the bevelled edges of the plate 28 to restore the same to its original position in the slot. The movement from the illustrated locking position to the opening position is on the contrary only possible if the three channels of said three flanges register with the teeth 18—29—30.

The rings 34—35—36 are held in position by means of ring 39 screwed on the fixed body 15 of the lock.

On each of the rings 34—35—36 there is arranged a drum respectively 40—41—42 the latter

50

55

being made in one piece with the protective cover 43 in whose internal cavity there is lodged the outside end of the fixed body 15 and the outside end of the moveable body 19. The drums 5 40—41 are handled by means of projecting tooth crowns 44 and 45 while the drum 42 is handled by means of the cover 43, which may be conveniently striated. The drums 40—41—42 are held in position by a fork 46 carried by a support 10 47 fixed to the frame 2 by means of a screw 48 provided with a knurled head 49. The drums 40—41—42 cooperate with rings 34—35—36 to which they can be keyed in any desired angular positions. For this purpose, as shown in Fig. 3, 15 the rings are substantially polygonal shaped on their outsides and the drums have corresponding internal shapes. Thus, it is possible to arrange the drums angularly with respect to the rings in such a way that the letters or numbers 20 engraved on the outer surface of the drums may be combined differently the combinations being previously established and easily modified at will by the owner or user of the bag.

The different angular positions of the drums 25 25 are made noticeable by means of springs 50—51—52 carried by the console shaped support 47 and cooperating with notches 53 provided in the peripheries of the drums.

As illustrated in Fig. 1 around the drums there 30 30 may be arranged cylindrical protection plates 54—55 provided with openings 56—57 which allow the reading of the combination of three letters or ciphers constituting the key of the combination of the lock.

35 The present invention has been illustrated and disclosed in a preferred form of realisation, but of course constructive modifications may be introduced without trespassing the limits of protection of the patent. For instance each of 40 the drums may be provided with a projecting tooth 58 capable of giving a tactile reference to the user of the device so that in the dark and

without looking it is possible to arrange the drums in a determined initial position and then to displace them one by one and counting the passages of the notches 53 on the springs 50—51—52.

Having now particularly described and ascertained the nature of my said invention and in what manner the same is to be performed, I declare that what I claim is:

1. In a lock of the character described, a tubular casing, a bolt mounted in said casing for reciprocation therein, and a series of coaxial individually rotatable tumblers surrounding said bolt and provided with notched inwardly-directed flanges, said bolt comprising a cylindrical element having a radial slot in its midportion and longitudinal bores on each side of said slot, a plate slidably mounted in said slot and provided with a series of projecting teeth cooperable respectively with said tumbler flanges, and yieldable resilient means in said bores bearing against 20 opposite ends of said plate to urge said teeth yieldably in a radial direction toward said tumbler flanges.

2. In a lock of the character described, a tubular casing, a bolt mounted in said casing for reciprocation therein, and a series of coaxial individually rotatable tumblers surrounding said bolt and provided with notched inwardly-directed flanges, said bolt comprising a cylindrical element having a radial slot in its midportion and longitudinal bores on each side of said slot, a plate slidably mounted in said slot and provided with a series of projecting teeth cooperable respectively with said tumbler flanges, and yieldable resilient means in said bores bearing against 25 opposite ends of said plate to urge said teeth yieldably in a radial direction toward said tumbler flanges, said yieldable resilient means comprising a plunger in each of said bores, and a compression spring behind it.

ATTILIO BENIGNI.
